HARRY HADEN, OF PITTSBURG, PENNSYLVANIA, ASSIGNOR TO H. C. FRY GLASS COMPANY, OF ROCHESTER, PENNSYLVANIA, A CORPORATION OF PENNSYLVANIA.

DESIGN FOR A GLASS VESSEL.

No. 39,993.

Specification for Design.

Patented May 18, 1909.

Application filed November 16, 1908. Serial No. 462,987. Term of patent 3½ years.

To all whom it may concern:

Be it known that I, HARRY HADEN, residing at Pittsburg, in the county of Allegheny and State of Pennsylvania, a citizen of the United States, have invented a new and original Design for Glass Vessels, of which the following is a specification, reference being had to the accompanying drawings, forming a part thereof.

The drawing shows a side elevation of a vessel having my design applied thereto.

I claim—

The ornamental design for a glass vessel as shown.

HARRY HADEN.
